CLAIM

The ornamental design for a double dab ink dauber, as shown and described.

DESCRIPTION

FIG. 1 is a front elevational exploded view of the double dab ink dauber showing my new design;
FIG. 2 is a rear elevational exploded view thereof;
FIG. 3 is a left side elevational view thereof;
FIG. 4 is a right side elevational view thereof;
FIG. 5 is a top plan exploded view thereof; and,
FIG. 6 is a bottom plan exploded view thereof.
The undisclosed surfaces of the double dab ink dauber form no part of the claimed design.
